UNITED STATES PATENT OFFICE.

ALGENON S. SPAULDING, OF WORCESTER, MASSACHUSETTS, ASSIGNOR TO
THE FLEXIBLE DOOR AND SHUTTER COMPANY, OF PORTLAND, MAINE.

FLEXIBLE DOOR.

SPECIFICATION forming part of Letters Patent No. 550,653, dated December 3, 1895.

Application filed November 2, 1891. Serial No. 410,607. (No model.)

To all whom it may concern:

Be it known that I, ALGENON S. SPAULDING, a citizen of the United States, residing at Worcester, in the county of Worcester and 5 State of Massachusetts, have invented certain new and useful Improvements in Flexible Doors, of which the following is a specification, reference being had to the accompanying drawings, forming a part of this specification, and in which—

Figure 1 represents a top view of a flexible door embodying my invention, the casing being shown in sectional view on line X X, Fig. 3, in order to disclose the pocket into which the 15 door is moved when opened, the door itself being represented as closed. Fig. 2 represents the same view as shown in Fig. 1, but with the door opened or moved into the pocket. Fig. 3 is a vertical sectional view of the door-casing on line X' X', Fig. 2. Fig. 4 is a vertical sectional view of the door-casing on line 20 Y Y, Fig. 2. Fig. 5 is a top view of three of the links forming the chain attached to the upper and lower ends of the leaves, which 25 constitute the body of the flexible door and which are represented in Fig. 5 by broken lines. Fig. 6 is a transverse sectional view of three of the leaves forming the body of the flexible door and illustrating their construction 30 and the mode of hinging them together. Fig. 7 represents the upper screw-threaded spindle and its inclosing screw-threaded sleeve shown in sectional view by which the upper edge of the flexible door is pivoted to the casing. Fig. 8 represents a bottom view of the part shown in Fig. 7. Fig. 9 is a side view of the adjustable bracket to which the 35 lower edge of the door is pivoted. Fig. 10 is a view of the same shown in section on line Z Z, Fig. 9. Fig. 11 is a top view of the 40 grooved plate upon which the bracket rests. Fig. 12 represents the casing of a window shown in sectional view to disclose the pockets at the sides of the window-opening and 45 showing a pair of flexible shutters shown in top view, one of which is extended into the window-opening and the other is contained within the pocket, and representing the application of my invention to a flexible window-shutter; and Fig. 13 represents in top or end 50 view a portion of the body of the flexible

shutter and showing a modified form and construction from that illustrated in Figs. 5 and 6.

Similar letters refer to similar parts in the different figures.

My invention has for its object to provide means by which a flexible door or shutter employed in closing the openings of doors or windows, or for similar purposes, can be suitably disposed within a pocket considerably 55 less in depth than the width of the door or window opening and sufficiently narrow to be inclosed within ordinary house-partitions, and also to provide means for the adjustment of the door when in place; and it consists in 60 the construction and arrangement of parts, as hereinafter described, and specifically set forth in the annexed claims.

Referring to Figs. 1 to 4, A A denote a box or casing inclosing a pocket A', into which 70 the flexible door is pushed in the operation of opening.

A² denotes a door-jamb, provided with an opening A³, through which the door is moved in and out of the pocket A'.

A⁴ denotes a groove in the threshold A⁵ along which the door is guided as it is drawn out of the pocket A' to close the door-opening, or, if preferred, the door can be guided by its upper edge, leaving the threshold 75 80 smooth.

The door, as represented in Figs. 1 to 4, consists of a series of leaves B⁴, hinged together at their edges and united to a slightly-heavier strip B, forming the door-stile, which is 85 brought against a door-jamb B', upon the opposite side of the door-opening, when the door is closed. The upper and lower ends of the leaves forming the body of the door are covered with metal plates B², hinged together 90 concentrically with the pintles uniting the edges of the leaves and having their edges turned over against the sides of the leaves, as at B³, Figs. 3 and 4, the links B² forming chains extending across the door at its upper 95 and lower edges. The form of the leaves B⁴, constituting the body of the door, is shown in cross-section in Fig. 6, having barrels B⁵ formed at their edges and pintles B⁶ by which the leaves are hinged together, each leaf consisting of a continuous strip extending 100 from the bottom to the top of the door,

as shown in Fig. 3, and having a series of short barrels interlocking each other on the opposing edges of adjacent leaves, which are united by pintles B^6 , held concentrically in the barrels.

- The flexible body of the door, formed in the manner described, is united at one edge to the stile B , and the opposite edge of the door is hinged to the door-casing by means of the 10 screws B^{6a} and B^7 . The screw B^{6a} is held in a screw-threaded sleeve B^8 , inserted in the header A^6 , or top of the box inclosing the pocket, and is provided with a flange B^9 , resting against the under surface of the header 15 A^6 , to which it is secured by screws passing through the holes B^{10} . The screw B^{6a} is provided with a square section B^{11} to receive a wrench and a cylindrical point B^{12} , entering the end of one of the links B^2 . The last leaf 20 B^{4a} of the door is cut away at its lower end to receive an angle-iron C , attached to the leaf B^{4a} and having a hole to receive the cylindrical point C' of the screw B^7 . The screw B^7 is held in the upper arm C^2 of the U-shaped 25 bracket C^3 and is provided with a square section C^4 to receive a wrench. The lower arm C^5 of the U-shaped bracket C^3 rests upon a plate D , attached to the floor by screws passing through the holes D' . The arm C^5 is provided 30 upon its under side with a rib C^6 , which rests in a groove D^2 in the upper surface of the plate D , and the bracket C^3 is adjustably attached to the plate D by a nut D^3 and a bolt D^4 , passing through a slot D^5 in the plate 35 D and held from turning within the slot by the flattened sides D^6 of the bolt. This construction allows the bracket C^3 to be moved along the plate D , so as to vary the alignment of the cylindrical point C' with the cylindrical point B^{12} , in order to change the angle 40 formed by the leaf B^{4a} with the floor and raise or lower the stile B . For example, if the bracket C^3 , as shown in Fig. 3, be moved toward the left, carrying the lower end of the 45 leaf B^{4a} , the whole body of the door will be tipped, raising the stile B farther from the threshold, for the reason that the several leaves, hinged together in the manner described, will form an unyielding body, except 50 as the several leaves are hinged together and capable of turning upon their pintles, and if the bracket C^3 be moved to the right, Fig. 3, the opposite result will follow and the stile B will be lowered. 55 It will be seen that the entire body of the door between the stile B and the leaf B^{4a} is hung upon the screws B^{6a} and B^7 with the lower edge of the door entirely free from contact with the floor A^7 of the pocket A' , and 60 also of the bottom of the groove A^4 , thereby allowing the door to be moved in and out of its pocket entirely free from frictional contact with the floor, and the adjustment, by moving the bracket C^3 , as already described, 65 allows the body of the door to be so inclined as to bring its lower edge parallel with the floor, over which it is to be moved, and in

case any variation should occur in the inclination of the floor, caused by the settling of the building or otherwise, the door-jamb A^2 70 can easily be removed and the necessary adjustment made by moving the bracket C^3 along its supporting-plate D and securing it in position by the nut D^3 and bolt D^4 .

At one side of the pocket A' , I place the 75 short strips E E , preferably at the top and bottom of the pocket, the inner faces of the strips being flush with the opening A^8 in the door-jamb A^2 and serving as guides, along which the leaves are moved as the door is 80 opened.

By referring to Fig. 6 it will be seen that each leaf is provided with an abutting shoulder F F , which are brought into contact as the door is extended, and the leaves are 85 brought into the same plane, thereby preventing the flexure of the door around its pintles, except in one direction.

Upon the side of the pocket opposite the guide-strips E E , I place the short strips G G , 90 against which the leaf B^{4a} strikes as the door is pushed into its pocket, the strips G G serving as stops to hold the leaf B^{4a} in a position parallel with the face of the guide-strips E E , and the successive movement of the door will 95 carry succeeding leaves into line with the leaf B^{4a} as it rests against the stop G , so that when the door is opened the several leaves composing it will assume the position shown in Fig. 2, a portion of the leaves extending from the 100 stile B along one side of the pocket and the remaining portion of the leaves extending from the leaf B^{4a} in a parallel line and occupying the opposite side of the pocket, the door being doubled upon itself and requiring a pocket whose depth will not greatly exceed one-half the width of the door-opening. The leaves extending from the leaf B^{4a} along one side of the pocket form a straight line 105 parallel with the leaves resting against the 110 guide-strips E , for the reason that they are held by the contact of the shoulders F F . Likewise the leaves after leaving the guide-strips E are held in a straight line by the shoulders F F , the two lines of leaves lying 115 parallel within the pocket and being crowded apart by the connecting-links, as illustrated by the links 1 2 3, Fig. 2.

The leaf B^{4a} can be raised or lowered by raising and lowering the screws B^{6a} and B^7 , 120 the square sections B^{11} and C^4 being provided to receive a wrench. The leaf B^{4a} is therefore capable of a vertical adjustment as well as a lateral adjustment at its lower end, and as the remaining leaves are hinged together 125 and to the leaf B^{4a} the adjustments already described will vary the position of the entire door.

By the above-described method of constructing and hanging the door it will be obvious 130 that one-half the door can be made solid instead of leaves hinged together, for example, leaves 4, 5, 6, 7, and 8, as they are received into the pocket in the same plane with the

stile B, might form a single solid panel rigidly attached to the stile or that portion of the door represented by the stile B, or leaves 4 to 8 might be framed in the same manner 5 as an ordinary panel-door and having the leaf 3 hinged to its edge. If the pocket were as deep as the width of the door-opening, that portion of the door used in closing the opening 10 might be an ordinary panel-door with a series of leaves hinged to one edge and to the screws B^{6a} and B⁷.

The lower end of the leaf B^{4a} is cut away to receive an angle-iron C to allow the adjustable bracket C³ and plate D to rest upon 15 the floor; but in case the bracket C³ and plate D were sunk in a recess below the surface of the floor the cylindrical point C', as well as the cylindrical point B¹² of the upper screw, might enter the ends of the leaf B^{4a}, which in 20 that case would preferably be made wider and heavier than the remaining leaves.

The metal links B² are formed with abutting edges H H, so they will be brought in contact, as the leaves to which they are attached are 25 brought into the same plane and perform the same function as the shoulders F F. Instead of a series of leaves hinged together, as already described, the flexible portion of the door may consist of a sheet of canvas, leather, or other 30 flexible material, as represented at I, Fig. 13, and having attached thereto strips (shown in end view at I', Fig. 13) and provided with abutting edges I², which are brought together as the strips I' are extended and brought in the 35 same plane, and preventing the flexible curtain so formed from being bent when in its extended position, except in one direction.

Fig. 12 represents a pair of shutters applied to a window-opening and consisting of 40 the flexible sections J, constructed of a flexible body covered by strips I', as above described and shown in end view, Fig. 13, hinged at one edge J' to the casing and attached at the opposite edge J² to a solid 45 panel J³. The shutters are drawn from opposite sides of the window-opening through openings J⁴, meeting in the center, and are hinged to the casing at J' in position to allow 50 a free space J⁵ to receive the sash-weights.

I do not confine myself to the specific forms 55 of construction as herein shown and described as constituting the flexible section of the door or shutter, as any known form of construction may be employed by which the inner edge of the flexible section can be hinged to the casing of the pocket or other fixed support at or near the opening through which the door enters the pocket.

In the construction shown in Figs. 1 to 4 60 the cylindrical points B¹² and C' serve as pintles upon which the inner edge of the door is hinged, and the screw B⁷ is provided with a shoulder K upon which the angle-iron C rests, allowing the leaf B^{4a} to be raised by 65 raising the screw B⁷, thereby lifting the entire body of the door.

I am aware that a shutter or curtain com-

posed of a series of strips flexibly united at their edges has been looped or doubled upon itself into a pocket or housing placed in a vertical plane, so the looped section of the curtain would fall by its own weight into the pocket and hang suspended therein, and I do not claim such.

The object of my invention is to secure the proper looping or doubling of the flexible door when it is moved in a horizontal plane into a pocket arranged at one side of the door or window opening. When the flexible curtain is allowed to fall into a pocket upon a lower plane and vertically, the weight of the curtain will serve to keep the looped section extended and the hinged strips in suitable position to be again drawn out of the pocket, for the strips are carried down in the pocket by their own weight, causing the looped section of the curtain to hang in two parallel lines, and when the strips or leaves of the curtain are drawn out of the pocket they are raised against the force of gravity. If the door is to be moved horizontally into the pocket, it becomes necessary to control the movement of the hinged strips as they are moved along the pocket, and I accomplish this by constructing the curtain with abutting shoulders so it is capable of being bent in one direction only, and arranging the two stop-pieces within the pocket as described, one of the stop-pieces G being arranged relatively to the pintles B⁶, on which the edge of the door is hinged, so that it will stop the strips or leaves in a position parallel with the line of motion of the door, and placing the edge of the second stop E parallel with that of the stop G and at a distance therefrom slightly greater than the width of one of the strips or leaves of which the door is composed, so that the stop G will hold the strip or leaf B^{4a} from swinging on the pintles B⁶ and hold it parallel with the movement of the door, and the leaves as they are pushed into the pocket will be held in a straight line against the stop E in the manner described.

What I claim as my invention, and desire to secure by Letters Patent, is—

1. The combination with a pocket arranged at one side of the door opening, of a flexible door composed of leaves hinged together at their edges and provided with abutting shoulders, whereby the door is held from bending, except in one direction, a fixed support to which one edge of said door is hinged within said pocket and a pair of stops arranged at opposite sides of the pocket, whereby the leaves of the door are looped in parallel lines within said pocket, substantially as described.

2. The combination of a pocket arranged at the side of the door, or window opening, a flexible door composed of a series of leaves hinged together at their edges and provided with abutting shoulders which are brought into contact when the door is extended, a fixed support carrying pintles to which one edge of the door is hinged, a stop G by which

the hinged edge of the door is restrained from swinging on said pintles, and a stop E arranged on the opposite side of said pocket to hold the leaves of the door in alignment as they enter the pocket, the distance between said stops being slightly greater than the width of the leaves composing the door, substantially as described.

Dated at Worcester, in the county of Worcester and State of Massachusetts, this 10 29th day of October, 1891.

ALGENON S. SPAULDING.
